(57) **CLAIM**

The ornamental design for a snap off popsicle stick, as shown and described.

DESCRIPTION

FIG. 1 is a front perspective view of a snap off popsicle stick, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines showing of a popsicle in the drawings depict environment that forms no part of the claimed design. All other broken lines depict portions of the snap off popsicle stick that form no part of the claimed design.
